UNITED STATES PATENT OFFICE

170,529

HINGE

Emil Hämmerli, Toronto, Ontario, Canada

Application October 1, 1951, Serial No. 16,798
In Canada June 26, 1951

Term of patent 14 years

(Cl. D10—9)

To all whom it may concern:

Be it known that I, Emil Hämmerli, a citizen of the Dominion of Canada, residing at Toronto, in the county of York and Province of Ontario, Dominion of Canada, have invented a new, original, and ornamental Design for a Hinge, of which the following is a specification, reference being had to the accompanying drawing, forming a part hereof.

Fig. 1 is a top plan view of a hinge showing my new design; and

Fig. 2 is a side elevational view thereof.

I claim:

The ornamental design for a hinge, as shown.
EMIL HÄMMERLI.
